[57] CLAIM

The ornamental design for a poker roll game housing, as shown and described.

DESCRIPTION

FIG. 1 is a perspective view of a poker roll game housing showing my new design;

FIG. 2 is a front elevation thereof;

FIG. 3 is a left side elevation thereof;

FIG. 4 is a top plan view thereof;

FIG. 5 is a right side elevation thereof; and

FIG. 6 is a rear elevation thereof;

The broken line showing of ball is for illustrative purpose and forms no part of the claim. The bottom surface is plain and unornamented.

*FIG. 1**FIG. 2**FIG. 3****FIG. 4******FIG. 5******FIG. 6***
